INVENTOR.

Thomas Lund

UNITED STATES PATENT OFFICE.

THOMAS LUND, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

HEEL-BREAST-TRIMMING MACHINE.

1,293,134.

Specification of Letters Patent.

Patented Feb. 4, 1919.

Application filed August 9, 1916. Serial No. 113,931.

To all whom it may concern:

Be it known that I, THOMAS LUND, a citizen of the United States, residing at Beverly, in the county of Essex and State of Massachusetts, have invented certain Improvements in Heel-Breast-Trimming Machines, of which the following description, in connection with the accompanying drawings, is a specification, like reference characters on the drawings indicating like parts in the several figures.

This invention relates to machines for operating upon the heels of boots and shoes after they are attached thereto and particularly to machines for shaping the breasts of such heels.

The invention is shown herein as embodied in a machine known to shoe manufacturers as the Louis heel breast trimming machine, which is shown and described in United States Letters Patent No. 784,340, granted March 7, 1905, on application of Benjamin F. Mayo. This machine is provided with a rotary cutter mounted on a horizontal shaft and with a shoe rest or support which is movable vertically to carry the heel breast across the field of operation of the cutter. The cutter is so formed and the shoe is so positioned relatively to it that, as the shoe support is moved vertically across the acting face of the cutter, a shape of breast is produced which is curved longitudinally in conformity to the shape of the cutter and which laterally of the shoe is a straight line by reason of the rectilinear vertical movement of the shoe support.

In modern shoe making a demand has arisen for heels which are formed with a convexity laterally of the shoe particularly at the portion of the breast nearest the shank of the shoe. When heels are thus formed, the side lines of the heel breast are preferably maintained as in heels having laterally straight breasts, each of these lines being a curve starting nearly straight at the tread face of the heel and extending inwardly and forwardly toward the toe of the shoe with gradually increasing curvature until it merges into the side line of the shank. A heel with a lateral convexity not only has a more stylish and finished appearance but also in such a heel there is more material in the part of the heel next the shank which

strengthens the heel and enables it to form a better support for the shank of the shoe. 55

An object of the present invention is to provide a machine which will produce a convex breast upon a heel particularly in that part of its face next the shank and preferably without altering the side line of the 60 heel or the lateral contour of the portion of the breast face next the top lift.

A feature of the invention consists in combination with a rotary cutter having its axis extending in a plane parallel to the longitudinal median plane of the shoe (that is, the plane in which the longitudinal axis of the shoe and the back seam lie) and having a contour to produce upon the heel, when the heel and cutter are moved relatively vertically, a laterally straight breast face, of means for moving the shoe and cutter relatively in said plane to cause the cutter to produce a laterally curved breast face. The breast face so formed is preferably convex 75 and the relative movement between the shoe and cutter may be effected, as shown herein, by a suitable templet and a coöperating roll placed the one upon a part fixed with respect to the cutter and the other upon a 80 part fixed with respect to the shoe. Preferably also, and as shown herein, the lateral convexity of the breast increases progressively from the breast face of the top lift where it is substantially straight to the 85 shank portion of the breast where the convexity is greatest.

These and other features of the invention will appear more fully from the following detailed description when read in connection with the accompanying drawings and will be pointed out in the appended claims. 90

In the drawings,

Figure 1 is a front view of a machine embodying this invention;

Fig. 2 is a side view of the head of the machine shown in Fig. 1;

Fig. 3 is a detail in perspective of the mechanism for moving the shoe support forwardly and rearwardly; and 100

Fig. 4 is a side view of the cutter and work support showing a shoe being operated upon, the cut being partially completed.

Referring to Fig. 1 of the drawings, the reference character 2 indicates the column 105 of the machine upon the top portion of

- which is mounted a shaft 4 having suitable means, as shown, for the application of power for rotating the shaft. Upon the left hand end of the shaft is mounted a rotary cutter, hidden in this figure but shown in end view in Fig. 2. The work supporting and positioning means comprises a member 10 having an upwardly extending arm carrying a plate 12 forming a rest against 5 the tread face of the heel is held with its breast face against a narrow rib or flange 14 on the plate 12. A lateral projection 16 of the member 10 is provided with clamping means 20 for adjustably holding a stem 22 10 which supports a rest 24 for the forepart of the shoe bottom. As the operator holds the shoe against the plate 12 and rest 24 the fingers of the right hand extend under the rear part of the shoe and may, as the shoe 15 is raised to carry the heel across the path of the cutter, accidentally contact with the cutter. To prevent this, a guard 30 is provided against which the fingers may rest in safety during the cutting operation. 20
- 25 The member 10 is adjustably fixed to the upper end of a longitudinally movable rod 32 which passes upwardly through a long vertical bearing in a member 34 and is moved upwardly by a treadle 36 connected therewith by a universal joint at 38. The rod 32 is prevented from rotating by a pin 40 carrying a roll that engages a vertical slot in the member 34. The member 10 is held non-rotatably upon the upper end of 30 the rod 32 by a nut 41 and the rib 14 of the plate 12 is arranged substantially over the longitudinal axis of the rod 32. By loosening the nut 41 the shoe positioning means 35 may be swung about the rib 14 as a center to vary the depth of cut made in the heel breast without varying the relation of the breast edge of the top lift to the cutter. 40
- The bearing member 34 has a dove-tailed portion engaging a lateral guide 42 and may 45 be adjusted laterally on said guide by means of a screw 44, being held in adjusted position by means operated by a hand wheel 46. This construction enables the position of the shoe support to be varied laterally relatively 50 to the cutter. The guide 42 is on a member 48, Fig. 2, which is mounted in turn on a guide 50 on the machine frame for to-and-fro or forward and rearward movement substantially at right angles to the shaft 4. 55 The member 48 is held rearwardly by a spring 52.
- Fixed to the post 32 above the member 34 and beneath the member 10 is a bracket 54, Fig. 3, on the rear face of which in that 60 figure is mounted a templet 60. The templet 60 has horizontal slots 62 and vertical slots 64 are provided in bracket 54 so that the templet may be adjusted both horizontally and vertically relatively to the bracket 54. A screw 65 passes through an

angularly bent end of the templet and determines, by contact with the bracket 54, the vertical position of the templet, which is held in adjusted position on the bracket 54 by bolts 66. On the fixed guide 50 forming part of the machine frame is a roll 70 which co-operates with the templet 60 to move the shoe support forwardly and rearwardly as it is moved vertically to carry the shoe across the face of the cutter, thereby determining the contour of the breast face of the heel, as shown in Fig. 4, giving the heel breast a convex face, the convexity of which is greatest at the portion nearest the shank and shades out to practically nothing at the portion of the breast nearest the tread face of the heel where the breast face is nearly parallel to the face of the cutter. 75 80

The cutter has the usual hood 80 and to the forward part of the hood 80 is slidingly connected at 82 a movable shield or guard 84 which normally covers the front of the cutter. The sliding connection mentioned comprises a roll mounted at 82 upon the hood 80 and engaging a curved groove 90 formed in the shield 84. The lower end of the shield is pivoted to one end of a link 85, the other end of which embraces the cutter shaft. The bracket 54 is connected by a link 86 to the link 85 and hence as the work support is raised the shield 84 is lifted to permit the work to engage the cutter. The link 86 is connected by universal joints to the link 85 and to the bracket 54, which connection enables the various adjustments and movements of the work support to be made without affecting the operation of the work support by the treadle 36. 95 100

Having fully described my invention, I claim as new and desire to secure by United States Letters Patent:

1. In a machine of the class described, the combination with a rotary cutter and a rest for the shoe constructed and arranged to position the shoe with the longitudinal median plane of the shoe parallel with the axis of the cutter and for movement across the acting face of the cutter, of means for moving the shoe and cutter relatively in said plane to cause the cutter to produce upon 115 the heel a laterally curved breast face.

2. In a machine of the class described, the combination with a rotary cutter and a rest for the shoe constructed and arranged to position the shoe with the longitudinal median plane of the shoe parallel with the axis of the cutter and mounted for movement across the acting face of the cutter, of means for moving the rest first away from the cutter and then toward the cutter to produce upon 120 125 the heel a convex breast face.

3. In a machine of the class described, the combination with a rotary cutter and a rest for the shoe constructed and arranged to position the shoe with the longitudinal median 130

- plane of the shoe parallel with the axis of the cutter and mounted for movement across the acting face of the cutter, of a stationary roll upon the machine frame, and a templet carried by the shoe rest and coöoperating with the roll to move the rest away from the toward the cutter to produce upon the heel a convex breast face.
4. A heel breasting machine having, in combination, a rotary cutter, a shoe rest against which the shoe is held by the hands of the operator, means for moving the rest to carry the work across the cutter in a direction from side to side of the heel, and means for simultaneously moving the heel toward and from the cutter to produce a lateral curvature of the breast.
5. In a heel breast trimming machine, a rotary cutter arranged to trim the breast of a heel from one side of the heel to the other side, in combination with a shoe support for sustaining the heel with its breast in acute angular position with relation to the plane of rotation of said cutter, and means to move the cutter and shoe support relatively in the direction of approach to and recession from the cutter during the cutting operation to form a curved breast.
6. In a machine of the class described, a rotary cutter, a support for presenting a shoe with the plane of its longitudinal axis and back seam parallel to the axis of the cutter, means for effecting relative movement of said support and said cutter to cause the cutter to trim the breast of the heel from one side of the heel to the other side, and means for relatively moving the shoe support and cutter in another direction to cause the cutter to form a laterally curved breast.
7. In a machine of the class described, a shaft, a rotary cutter thereon, a shoe support having means to engage the heel breast and top lift of the shoe and maintain the breast with the heel in acute angular relation to the longitudinal axis of the shaft, means for moving the support to carry the heel across the acting face of the cutter, and means for moving the shoe support from and toward the face of the cutter during the movement of the shoe support to carry the heel across the cutter.
8. In a machine for trimming the breasts of heels, a vertically movable rod, a shoe rest supported thereon, the rest being adjustable on the axis of the rod as a center, a lip on the rest for positioning the breast edge of the top lift of the heel, the said lip being substantially in alinement with the axis of the rod in different positions of adjustment of the rest whereby the cut made in the heel to form the breast will always start uniformly with relation to the edge of the top lift, and means for moving the rest relatively to the cutter to form a laterally convex face on the heel breast the convexity of which increases progressively from the top lift toward the shank of the shoe.
9. In a machine of the class described, the combination of a cutter having a peripheral cutting face and a side cutting face, a horizontal shaft carrying the cutter, a shoe rest arranged for vertical movement across the cutting face of the cutter and having means for locating the breast edge of the top lift with relation to the side face of the cutter so that little or no stock will be removed by the cutter from said breast edge, means whereby adjustment of the rest may be effected about a vertical axis lying substantially in the breast edge of the top lift to vary the amount removed by the cutter from the remainder of the heel, and means for moving the rest horizontally as it is moved vertically to form a convex breast face on the heel next the shank without materially affecting the relation of the portion of the breast face next the top lift to the side face of the cutter.
10. A machine of the class described having, in combination, a rotary cutter having a horizontal axis, a shoe support having a portion to engage the tread face of the shoe heel constructed and arranged to position the shoe with its longitudinal median plane horizontal and against which support the shoe is held by the hands of the operator, means for moving the shoe support vertically to carry the heel breast across the face of the cutter, and a guard comprising a relatively thin plate extending laterally across the face of the cutter and formed on the shoe support beneath the portion which engages the tread face of the heel and adapted to prevent the fingers of the operator's hand which holds the heel portion of the shoe from coming into accidental contact with the cutter as the shoe is moved vertically across the cutter.
11. In a machine of the class described, a tool, a shield for the tool arranged independently of the tool and movable to expose said tool, a roll above the tool having a curved groove connection with the shield, means for guiding the lower end of the shield, a work support arranged to support work normally out of operative relation to the tool and movable relatively to the tool to bring the work into contact with the tool, and a positive connection between the shield and the work support.
12. In a machine of the class described, a tool, a shield for the tool arranged independently of the tool and movable to expose the tool, a work support arranged to support the work normally out of operative relation below the tool and movable relatively to the tool to raise the work into contact with the tool, means for causing the work support as it is raised to move from and toward the tool, means for adjusting the work support

4
relatively to the tool at right angles to its to and fro movement, and a link having universal joint connections at one end to the shield and at the other end similar connections to the work support.

5 13. In a machine of the class described, the combination of a rotary cutter arranged for rotation in a vertical plane, a shoe support constructed and arranged to position a
10 shoe on its side for presentation of the heel breast to the cutter and movable vertically to carry the heel across the field of operation

of the cutter, said support including a plate constructed and arranged to engage and position the tread face of the top lift of the 15 heel relatively to the cutter, and means for adjusting the shoe support and plate longitudinally of the cutter shaft so that the plate may be located close to the cutter but out of contact therewith.

20 In testimony whereof I have signed my name to this specification.

THOMAS LUND.

It is hereby certified that in Letters Patent No. 1,293,134, granted February 4, 1919, upon the application of Thomas Lund, of Beverly, Massachusetts, for an improvement in "Heel-Breast-Trimming Machines," an error appears in the printed specification requiring correction as follows: Page 3, line 6, claim 3, for the article "the" read *and*; and that the said Letters Patent should be read with this correction therein that the same may conform to the record of the case in the Patent Office.

Signed and sealed this 25th day of November, A. D., 1919.

[SEAL.]

M. H. COULSTON,

Acting Commissioner of Patents.
